QUICK CHANGE MOUNTING MEANS FOR
SWITCHBOARD METERS AND THE LIKE
Wayne E. Broyles, P.O. Box 2572, Houston, Tex. 77001
Filed Jan. 20, 1967, Ser. No. 610,619
5 Claims. (Cl. 339—126)

ABSTRACT OF THE DISCLOSURE

A mounting for meters whereby a meter may be quickly mounted on or removed from a display panel by the use of jack plugs in lieu of the terminal posts to which electrical leads are normally connected to panel mounted meters. The jacks are plugged into registering female sockets permanently mounted in a secondary panel part rigidly fixed to the panel in spaced relationship with respect to the inner side by means of adjustable nuts and bolts. With this arrangement, a meter is merely plugged into its position of use or unplugged therefrom without the necessity of connecting and disconnecting wires and/or fastening elements.

This invention relates to means for quickly connecting and disconnecting electrical instruments such as meters to and from switchboards and the like.

The object of the present invention is to eliminate the time consuming procedure required for mounting and demounting instruments on and from switchboards by replacing the usual threaded binding posts for the electrical leads with plugs on the rear of the instrument which match up with cooperating sockets more or less permanently fixed to the switchboard.

Other objects and their attendant advantages will become apparent as the following detailed description is read in conjunction with the accompanying drawings wherein:

FIG. 1 is an exploded view showing the quick connect instrument mounting means of the present invention;

FIG. 2 is a side elevational view of the assembled 41) mounting means of FIG. 1; and

FIG. 3 is a top elevational view of the mounting means of FIG. 2.

Referring now to the drawings, the numeral 10 designates a part of a conventional electrical switchboard which may be adapted to receive a wide variety of meters and other instruments conventionally found on such boards and as is customary the board is provided with a plurality of openings, one opening 12 being shown in the drawings. The opening 12 is adapted to receive the body part 14 of a meter 16 having the usual dial face 18 including a flange 20 which is conventionally provided with two or more threaded studs 22 or the like adapted to be received in drilled openings 24 in the board 10 to receive nuts 25 as shown.

In lieu of the usual threaded mounting posts for receiving the electrical leads at the rear of the instrument, in accordance with the invention there are substituted for the mounting posts plugs 26 similar to phone jacks and these plugs are adapted to be slidably received within female socket members 28 carried in a small separate panel member 30 spaced away from the rear of the main board. The socket members 28 terminate on the rear side of the small panel member 30 in binder posts 32 similar to those which are otherwise normally carried directly on the back of the instrument itself.

The small panel member 30 is mounted in spaced disposition rearwardly of the main switchboard 10 by means of bolts 36 which extend through aligned openings in the board 10 and in the small panel part 30 with the bolts

2

being adapted to receive nuts 38 adjacent the rear of the board 10 and which when tightened against the rear face thereof firmly locate the bolts 36 in their position of use. In addition the bolts receive nuts 40, 42 which sandwich between them the end parts of the small panel member 30, the arrangement being such that the panel member 30 can be accurately positioned towards or away from the rear face of the board 10 as necessary so that the jack plugs 26 are properly received in the sockets 28. If desired, separate binder post means 44 may be carried by the small panel part 30 to receive a resistor or the like and the inner ends of the jack plugs 26 may be provided with O-rings 46 which sealingly engage the exposed parts of the socket members 28 to seal out moisture from the meter terminal contacts.

From the foregoing description it will be seen that after the small panel member 30 has been properly located with respect to the board 10, any meter equipped with the appropriate jack plugs 26 can be mounted onto the board 10 in a matter of seconds by merely plugging the jack plugs into the socket 28 and at the same time the small threaded studs 22 register with the openings 24 in the switchboard to properly position the instrument against twisting and the like and if desired, the studs may be provided with nuts 25 shown. When the instrument is to be replaced, the operator merely grasps the front panel thereof and pulls the instrument directly outwardly and may, if he so desires, immediately replace it with a second instrument of similar construction and configuration as the first.

It will be apparent from the foregoing description that the quick connect means of the invention is susceptible of a variety of changes and modifications without however departing from the scope and spirit of the appended claims.

What is claimed is:

1. In combination with a switchboard or the like and an electrical instrument, said board having an opening therein for slidably receiving said instrument, mating plug and socket members, some of which are carried by said instrument and the others of which are carried on said board in a substantially permanent disposition relative to said opening, and means for connecting the board-carried members to a source of electrical energy, said plug and socket members being constructed and arranged to slidably inter-engage or disengage when said instrument is inserted into or removed from said opening, including O-rings received on said plugs and sealingly engaging said sockets.

2. The combination of a switchboard or the like and an electrical instrument, said board having an opening therein for receiving said instrument, mating plug and socket members, an individual panel member, some of said mating plug and socket members being carried by said instrument and the others being carried on said individual panel member, means for fixedly and adjustably securing said panel member to the board in spaced relationship with respect to the rear face thereof and with said members carried thereby positioned with respect to said opening to cooperate with the members carried by said instrument when the latter is in its position of use on said board, and means for connecting the panel-carried members to a source of electrical energy, said plug and socket members being constructed and arranged to slidably inter-engage or disengage when said instrument is inserted into or removed from said opening.

3. The combination of claim 2 wherein said adjustable securing means comprises rearwardly extending threaded members rigidly fixed to said board, and adjustable nut means received on said threaded members and cooperating

3

with said panel member to secure said member in a pre-selected spaced position with respect to the rear face of said board.

4. The combination of claim 2 including electrical binding posts connected to the rear face of said panel member, each of said posts being connected to one of the panel-carried members.

5. The combination of claim 2 wherein said instrument includes a face flange, at least one positioning element extending rearwardly of said face flange, said board having an opening therein receiving said element to position said instrument against twisting with respect to its opening.
